UNITED STATES PATENT OFFICE

JOSEPH F. DICKSON AND ROBERT M. TURNER, OF KEWANEE, ILLINOIS, ASSIGNEES,
BY MESNE ASSIGNMENTS, TO KEWANEE BOILER COMPANY, OF KEWANEE, ILLINOIS,
A CORPORATION OF DELAWARE

BOILER

Application filed December 3, 1927. Serial No. 237,393.

This invention pertains to certain features of betterment, both structural and functional, in boilers, heaters and similar constructions made of sheet-metal, one of the leading and principal objects and purposes being the provision of an appliance of this type which is so constructed that it requires less stay members than usual to give it adequate strength, which eliminates riveting more or less, or entirely, which affords a better arrangement for the efficient circulation of the water undergoing heating, and which can be manufactured relatively inexpensively.

To the attainment of these and other desirable aims, a present, preferred embodiment of the invention has been completed, which is illustrated in detail in the accompanying drawings, forming a part of this specification and to which reference should be had in connection with the following description, like reference numerals being used throughout the several views to designate the same parts.

In these drawings:—

Figure 1 is a central, longitudinal, vertical section through the novel and improved boiler;

Figure 2 is a vertical cross-section through the boiler on line 2—2 of Figure 1, the parts being viewed in the direction indicated by the arrows;

Figure 3 is a similar section on line 3—3 of Figure 1, the elements being viewed in the opposite direction, as shown by the correlated arrows;

Figure 4 is an elevation of the shaped sheet-metal element forming parts of the supplemental combustion chamber;

Figure 5 is side elevation of the same member; and

Figure 6 is a plan view of the same part.

Referring to these drawings, it will be observed that the general style and form of the sheet-metal boiler with internal fire-box is not new, the invention residing in certain structural details which will presently be made plain.

As is shown, the boiler has a main combustion-chamber or space 11, which connects directly at its rear with a supplemental com-

bustion-chamber 12 rising somewhat higher than the chamber 11, the latter having an upwardly - arched, transversely - corrugated crown-sheet 13 which is integral with the vertical plates 14 and 15 constituting the inner walls of the two, side water-legs 16 and 17, the outer walls 18 and 19 of which form parts of the main boiler shell or casing 21.

The front of the boiler has the usual wall or plate 22 provided with a doorway 23, that portion of the front wall below the crown-sheet having a water space 24 formed in conjunction with the wall 22 by a suitably-shaped, inner plate 25, the rear of the boiler having the customary back plate 26.

Tubes or flues 27 extend through proper, aligned apertures in the front and back plates and join the connection 28 with the chamber 29 associated with the stack, shorter tubes 31 connecting the lower part of the member 28 with that portion of the supplemental combustion-chamber 12 at a higher level than the main compartment or fire-box 11 through a properly-shaped, apertured flue-sheet 32.

The top or crown-sheet, the inner back-wall and both inner side-walls of the supplementary fire-box 12 are formed of a single, sheet-metal, plate-member, characterized as a whole 30 and shaped as shown in Figures 4, 5 and 6, such back and side walls being spaced inwardly away from the corresponding outer sheets 26 and 18 and 19 to supply the rear water-leg 33 and extensions of the side water-legs 16 and 17, as will be readily understood.

Such member 30 comprises an upright back-wall 34, a top or crown-sheet wall 35, and opposite vertical side-walls 36, 37, the back-wall joining the crown-sheet portion by means of a curved section 38 of substantially-uniform curvature throughout the width of the portions which it joins together, and, in similar manner, the side-walls 36 and 37 are connected to the crown-sheet section by uniformly curved or rounded parts 39, 39.

On the other hand, however, the back-wall 34 is joined to both adjacent side-walls 36, 37 by curved or rounded sections 41, 41 which are not of the same width or extent throughout their length, but taper downwardly in

material degree so that at their bottoms the corners or edges are almost square.

The two side-walls are slightly notched at 42, and the flue-plate 32 is fitted in the upper 5 portion of the mouth or open front side of the shaped member 30, its top and side edges being welded to the inner surfaces of such member, its lower edge being welded or otherwise suitably fastened to the crown- 10 sheet 13.

The lower portions of the side-walls 36, 37 are in register or alignment with the side-walls 14 and 15, and the edges of the plates 36 and 14 and 37 and 15 are welded together 15 in butting relation.

Thus the back, top and side walls of the complementary or auxiliary fire-box or combustion-chamber are provided by a single, suitably-shaped, metal plate which is welded 20 to the other parts of the structure, hence avoiding the undesired riveting.

Such element 30, by reason of its several strengthening and stiffening curved or rounded sections, is adequately and sufficiently 25 braced by its own inherent form and shape to materially decrease the amount of staying required to give the structure the proper strength, and, although stay-bolts 43 are used to secure together the spaced plates 26 and 30 34 and other like members 44 are employed to tie together the side-wall plates 36 and 18 and 37 and 19, the number of such parts used is less than customary and their proximity to the curved portions of the member 30 is 35 less because the latter are strong and rigid enough to brace the adjacent flat or plane portions of the plates some little distance from them.

Other stay-bolts 45 are used to join together the separated plates 14 and 18 and 15 and 19 and opposite sides of the boiler may be fastened together by cross tie-rods 46.

The top portion of the combustion-compartment 12 is extremely hot during the 45 operation of the boiler, and, for that reason, it is desirable to provide a construction which will aid the efficient circulation of the water at this part of the boiler, the rounded surfaces specified accomplishing this object, as well as the other advantages just enumerated.

In view of the fact that the upper parts of the water legs at the rear and sides of the supplementary fire-box are more highly heated than their lower portions, the tapering of the 55 rounded surfaces 41, 41 affords an effective means for attaining an especially beneficial upward flow of the water in such legs as it becomes heated and rises being replaced below by cooler water.

The invention, as presented, and as defined by the appended claims, is susceptible of a variety of embodiments and is not necessarily restricted to the details of structure of the particular preferred boiler selected as a suitable example.

We claim:

1. In a heater having a main combustion-chamber and a supplemental combustion-chamber connected with the rear of said main-chamber and extended higher than the latter, a first metal plate forming the outer shell of the boiler and the outer side-walls of both chambers, a second front-wall plate for the boiler, a third rear-wall plate for the boiler, a fourth single metal plate forming the 70 crown-sheet and the inner side-walls of said main-chamber, a fifth single metal plate forming the crown-sheet, the inner side-walls and the inner rear-wall of said supplemental-chamber, a sixth flue-sheet secured to said 75 fifth plate and to the crown-sheet of said main-chamber, and flues connecting said flue-sheet and said front-wall plate, said side-wall portions of said fourth and fifth plates being welded together, the junctions of said crown-sheet of said fifth plate with its rear and side wall portions being curved, and the junctions of said side and rear walls of the same plate being curved and downwardly tapered. 80

2. In a heater having a main combustion-chamber and a supplemental combustion-chamber connected with the rear of said main-chamber and extended higher than the latter, a first metal plate forming the outer shell of the boiler and the outer side-walls of both chambers, a second front-wall plate for the boiler, a third rear-wall plate for the boiler, a fourth single metal plate forming the crown-sheet and the inner side-walls of said main-chamber, a fifth single metal plate forming the crown-sheet, the inner side-walls and the inner rear-wall of said supplemental-chamber, a sixth flue-sheet secured to said 90 fifth plate and to the crown-sheet of said main-chamber, and flues connecting said flue-sheet and said front-wall plate, said side-wall portions of said fourth and fifth plates being welded together, the junctions of said crown-sheet of said fifth plate with its rear and side wall portions being curved, and the junctions of said side and rear walls of the same plate being curved and downwardly tapered. 95

3. In a heater having a main combustion-chamber and a supplemental combustion-chamber connected to the rear of, and extending higher than, said main combustion-chamber, the combination of a metal plate forming the outer shell of the heater, a front-wall plate for the heater, a rear-wall plate for the heater, a metal plate forming the crown-sheet and inner side-walls of said main combustion-chamber, a sheet-metal structure forming the crown-sheet, the inner side-walls and the inner rear-wall of said supplemental combustion-chamber, a flue-sheet secured to said crown-sheets and to the side-walls of said structure, flues connecting said flue-sheet and front-wall plate, the marginal portions of the 125

130

inner side-walls of said combustion-chambers being secured together, the junctions of the side and rear walls of said structure being curved and downwardly tapered.

5 In witness whereof we have hereunto set our hand.

JOSEPH F. DICKSON.
ROBERT M. TURNER.

CERTIFICATE OF CORRECTION.

Patent No. 1,748,945.

Granted March 4, 1930, to

JOSEPH F. DICKSON ET AL.

It is hereby certified that the name of the assignee in the above numbered patent was erroneously written and printed as "Kewanee Boiler Company, of Kewanee, Illinois, a corporation of Delaware", whereas said name should have been written and printed as "Kewanee Boiler Corporation, of Kewanee, Illinois, a corporation of Delaware", as shown by the records of assignments in this office; and that the said Letters Patent should be read with this correction therein that the same may conform to the record of the case in the Patent Office.

Signed and sealed this 25th day of March, A. D. 1930.

(Seal)

M. J. Moore,
Acting Commissioner of Patents.
